UNITED STATES PATENT OFFICE.

EARL V. GARRETT, OF TAMAQUA, PENNSYLVANIA.

ICE-CREAM CABINET.

Application filed February 10, 1925. Serial No. 3,255.

To all whom it may concern:

Be it known that I, EARL V. GARRETT, a citizen of the United States, residing at Tamaqua, in the county of Schuylkill and State of Pennsylvania, have invented certain new and useful Improvements in Ice-Cream Cabinets; and I do hereby declare the following to be a full, clear, and exact description of the invention, such as will enable others skilled in the art to which it appertains to make and use the same.

The present invention relates to improvements in ice cream cabinets, and has for an object to provide an improved cabinet useful in connection with the retailing of ice cream and similar commodities, in which the cans or containers of the ice cream are introduced and supported in the cabinet at an angular position to the usual vertical arrangement whereby greater convenience in access to the containers may be had with less likelihood of contamination of the contents.

Another object of the invention resides in providing a cabinet of the kind stated in which the angular or diagonal arrangement of the containers provides space above such containers for the refrigerant to the end that the cold air may circulate downwards upon all parts of the container as long as there is any of the refrigerant remaining.

The invention also contemplates the construction of a cabinet in which the top is made available for use as a counter or fountain; wherein the inner wall of the cabinet provides for holding and concealing utensils employed in connection with such cabinets; and wherein the refrigerant receptacle is mounted as a unit within the cabinet and provided with a drain valve which lies wholly within the cabinet; the drain may be connected through any part of cabinet to sewer if desired.

With the foregoing and other objects in view, the invention will be more fully described hereinafter, and will be more particularly pointed out in the claims appended hereto.

In the drawings, wherein like symbols refer to like or corresponding parts throughout the several views:

Figure 1 is a rear elevation of an improved ice cream cabinet constructed in accordance with the present invention;

Figure 2 is a horizontal section taken on the line 2—2 in Figure 3; and

Figure 3 is a vertical central section taken transversely through the improved cabinet.

Referring more particularly to the drawings, the cabinet is constructed of the front substantially vertical wall 4, the substantially vertical end walls 5 and 6 and the rear wall 7, arranged at an angle with respect to the vertical or disposed diagonally outwardly of the cabinet space. The cabinet is closed by the bottom 8. The bottom is raised and the rear and front walls 4 and 7 may be given suitable ornamental configuration at the bottom, as indicated at 9 in Fig. 1. The lower portion 10 of the rear wall 7 may be disposed in a vertical plane, so as to form an appropriate leg for the cabinet and appropriate support to which to attach the bottom 8. The upper portion 11 of the rear wall is also preferably disposed vertical and in a line with the lower part 10. At the innermost upper portion of the diagonal part of the rear wall 7 in the embodiment shown in the drawings is arranged a board 12 extending substantially vertical and meeting with the closure plate 13, which extends in a reverse diagonal or angular relation with respect to the lower portion 7 of the wall for the purpose of joining the upper end of the board 12 with the lower end of the upper wall portion 11. The plate 13 is provided with openings above each of the container spaces 14 arranged diagonal or at an angle within the cabinet substantially parallel with the diagonal inner wall 7, these spaces being fashioned out of the insulating material 15, which is contained in the cabinet. The insulating material may be thick in a transverse direction owing to the bulged character of the inner part of the container and hence the rapid dissipation of the cold inner atmosphere of the cabinet may be to a better degree prevented. The spaces 14 are closed individually by the lids or covers 16 fitted in the openings in the closure plate 13. These lids or covers may correspond to those usually placed upon the top of the standard vertical cabinet. The cans or containers are indicated at 17 and these are removably placed in the spaces below the cover plates and assume the inclined position

indicated in Fig. 3. The can covers are indicated at 18 and it will be noted that the entire can from the cover down to the base is situated below some part of the refrigerant receptacle 19, which is supported in the upper part of the vertical portion of the cabinet. The cans preferably rest upon crescent-shaped sleeves or cradles 20 shown to advantage in Fig. 2, and made from metal or some other appropriate material, with the edges or legs 21 bent downwardly to engage the lower wall of the space 14. These sleeves or cradles take the strain off the insulated walls of the cabinet when shifting the heavy cans in and out of the cabinet, and they also support the cans and hold them in proper position beneath the openings in the cover plate. The bottom of the insulating body is inclined as indicated at 22 to agree with the inclined position in which the cans 17 are to be held. The lateral space 14 in the insulating material communicates at its lower end with the vertical space 23 in the insulating material 24 of the main or vertical part of the cabinet. The refrigerant receptacle 19 extends in the upper part of this space 23, and its lower end may be shaped to extend along the containers 17. For this purpose, in the embodiment shown in the drawings, the lower part of the refrigerant receptacle is of substantially hopper shape with a drain valve 25 situated at its lowest point and within the cabinet. The refrigerant receptacle is supported in any appropriate manner, as for instance by the metal or other straps 26 affixed to the beams 36 or counter 27 above the vertical part of the cabinet.

The counter 27 is preferably hinged along its forward edge as indicated at 35 to permit this counter to be raised when access to the ice receptacle is to be had. A sub-counter 38 closes the upper portion of the vertical part of the cabinet, except that an opening having a sloping or other wall 28 is provided through this sub-counter to receive the cover 29 for the ice receptacle. The entire cabinet is also preferably lined throughout with a water proof lining indicated at 37.

In the use of the device, the cabinet is useful as a counter, the top of which may be removable or on hinges, and the ice cream or other commodity kept in the cabinet may be served upon the counter 27, which forms a convenient support for soda water fixtures. The inclined wall 7 may also be used for supporting utensils used in connection with the dispensing of the ice cream. The overhead icing chamber is exposed to the outside temperature only when icing, which will occur probably about twice a week, and the refrigerant is kept entirely apart from the containers in which the ice cream is held, so that there is no opportunity for the salt or ice to get into the cream, and moreover the

arrangement will prevent contamination of the product. The cans are not required to be packed with ice and salt, and consequently, the wear of the cans will be materially decreased as well as the time in performing this work saved. The ice cream will be kept always hard and firm at the top of the can, owing to the overhead arrangement of refrigerant, and the dipping into the can when serving the ice cream is rendered easy, owing to the slope or angle at which the cans are held. Material decrease in the amount of ice and salt will occur, and space in the store will be conserved by utilizing the device as a combined cabinet and counter.

The device also will permit of the ice chamber being locked, to prevent the dealer from placing meats or other extraneous commodities on the ice, or from removing ice for refrigerator or domestic use, or for use in connection with the dispensing of soft drinks.

By virtue of the fact that the drain valve is placed on the inside of the refrigerator, no loss of refrigeration from this source can occur. With the arrangement shown, the outside of the cabinet will be prevented from sweating and destroying the finish. The life of the cabinet is greatly increased over the cabinets in use at present, since no tamping is needed.

What is claimed is:

1. An ice cream cabinet comprising a substantially vertical portion and a diagonal portion intersecting the vertical portion and providing spaces for the circulation of air, containers arranged angularly in said diagonal portion and extending into the lower part of the vertical portion, and a receptacle for holding refrigerant out of contact with the containers and for cooling the air in said air spaces and promoting a circulation thereof about the containers, said refrigerant receptacle being placed in the upper part of the vertical portion of the cabinet and being above said containers.

2. An ice cream cabinet comprising a main substantially vertical portion and a lateral diagonally extending portion, insulating material lining the walls of both portions of said cabinet and having a substantially vertical space in the main portion of the cabinet and a diagonally extending space in the lateral portion of the cabinet, said spaces communicating at the lower parts thereof for the continuous circulation of cold air, a receptacle suspended in the upper portion of the space within the main cabinet part for holding refrigerant material out of said spaces and for promoting a circulation of cold air through said spaces, means for receiving containers in the diagonal space of the lateral part and for holding such containers with all parts thereof extending substantially beneath the refrigerant receptacle, and means

for giving access to the refrigerant receptacles and said containers individually.

3. An ice cream cabinet comprising a main substantially vertical portion having a closed top and a lateral portion, insulating material lining the walls of both portions of said cabinet and having spaces therein communicating at the lower parts thereof, one of said spaces extending into the lateral portion and 10 arranged diagonally with an inclined base to receive containers of ice cream and the like, inclined cover plates for the lateral part of the compartment through which access may be had to the containers, and a 15 receptacle extending in the upper portion of the main part of the cabinet below said closed top for holding refrigerant material out of contact with the containers and open spaces beneath said receptacle and about the

containers, and means for giving access to 20 the refrigerant receptacle through or under said top.

4. An ice cream cabinet comprising a substantially vertical portion and an adjoining lateral portion with communicating air 25 spaces in both said portions, cans held diagonally in said lateral portion, a receptacle held above said cans in the vertical portion of the cabinet for holding refrigerant material out of contact with said air spaces and 30 the cans and for promoting a circulation of cold air through the spaces and about said cans, a sub-counter above said refrigerant receptacle having an opening therein, a cover plate for the opening, and a main counter 35 hinged to said cabinet above said sub-counter.

EARL V. GARRETT.
